Inventor:

J. E. Hitt

Attorneys.

UNITED STATES PATENT OFFICE.

JOHN E. HITT, OF GOODLETTSVILLE, TENNESSEE.

RATCHET-WRENCH.

1,060,185.

Specification of Letters Patent. Patented Apr. 29, 1913.

Application filed April 23, 1912. Serial No. 692,668.

To all whom it may concern:

Be it known that I, JOHN E. HITT, citizen of the United States, residing at Goodlettsville, in the county of Davidson and State of Tennessee, have invented certain new and useful Improvements in Ratchet-Wrenches, of which the following is a specification.

My invention relates to improvements in wrenches and more particularly to that type of wrench commonly known as a ratchet wrench, and the object of my invention is to provide a wrench of the above described character in which the chuck or nut engaging member is provided with a relatively large socket adapted to receive one of a plurality of members provided with nut engaging sockets of various sizes, thereby adapting the wrench for use with all sizes of nuts. A further object of my invention is the provision of an improved ratchet mechanism, and means for adjusting the same to lock the chuck against rotation in either direction desired. And a still further object of my invention is to improve the construction and increase the efficiency of wrenches of the above described character.

With these and other objects in view, my invention will be more fully described, illustrated in the accompanying drawing, and then specifically pointed out in the claims which are attached to and form a part of this application.

In the drawing: Figure 1 is a top plan view of my improved wrench with the face plate removed to show the ratchet mechanism, the greater portion of the handle being broken away to permit the showing of the wrench upon an enlarged scale; Fig. 2 is a longitudinal section on the line 2—2 of Fig. 1; Fig. 3 is a transverse section on the line 3—3 of Fig. 1, showing the locking pawls and the manner in which they are mounted in the head of the wrench; Fig. 4 is a perspective view of the chuck or rotating member of the wrench; Fig. 5 is a perspective of one of the double-armed pawls employed in locking the chuck against counterrotation; Fig. 6 is a perspective of a modified form of detachable nut engaging member employed in connection with the chuck to adapt the wrench for use in removing the nuts from wheel spindles.

Corresponding and like parts are referred to in the following description and indicated

in all the views of the accompanying drawing by the same reference characters.

The preferred embodiment of my invention includes a hand grip or handle 10 enlarged at one end to form an integrally formed wrench head 11 in which is inclosed the ratchet mechanism, designated as a whole by the numeral 12, which controls the rotation of a chuck or nut engaging member 13 which is mounted for rotation in the forward portion of the head.

The head, as shown, is substantially elliptical in outline having parallel upper and lower faces and provided with a transversely formed opening 14 adjacent its free end, 70 said opening being cylindrical in contour and counterbored to form annular shoulders 15 and 16 spaced from the upper and lower faces of the heads.

Rotatably mounted in this opening, is the 75 chuck member 13, the lower end of which is reduced to form an encircling shoulder 17 which seats upon the shoulder 15. The upper end of the chuck bears against the face plate 18 which covers the ratchet mechanism 12 and which extends slightly inward over the peripheral edge of the chuck member, as shown in Fig. 2 of the drawing. This chuck member 13 is provided with a radially formed nut receiving recess 19 80 which in one position of the chuck registers with a slot 20 formed through the outer end of the head. The inner face of this nut receiving recess is formed with a cylindrical socket 21, while the opposite faces of the 90 recess are grooved longitudinally as shown at 22 in Fig. 4, these grooves forming continuations of the grooves 23 formed in the opposite faces of the slot 20 when the chuck occupies the position shown in Figs. 1 and 95 2 of the drawing. The reasons for this particular construction, together with the functions performed thereby will be hereinafter fully explained.

The peripheral face of the chuck member 100 13 is provided with two sets of outwardly directed ratchet teeth, one set being formed above the other and the teeth of one set being directed in one direction, while the teeth of the other set are directed in the opposite direction, the upper teeth 24, as shown in the drawing, being adapted to hold the chuck against clockwise rotation, while the lower teeth 25 are adapted to lock the chuck against movement in the opposite direction. 110

The intermediate portion of the head 11 is recessed to form pawl receiving chambers 26 and 27 formed one upon each side of the head and adapted to receive the double-armed locking pawls 28 and 29, one of which is clearly shown in Fig. 5 of the drawing. These pawls are mounted in proper position in the chambers by means of upper and lower trunnions 30 and 31, the former of which are seated in sockets 32 formed in the base of the chambers, and the latter of which are seated in similar sockets 33 formed in the inner face of the face plate 18. As best shown in Fig. 5, each of these pawls is formed with a pair of oppositely directed arms 34 and 35, the upper arms 34 being adapted for engagement with the teeth 24 of the chuck member, while the lower arms 35 are adapted for engagement with the teeth 25 of said chuck member. It will therefore be seen that the pawls may be swung in such a manner as to bring the arms 34 of both pawls into engagement with the upper ratchet teeth of the chuck or to bring the arms 35 both into engagement with the teeth of the lower ratchet. It will further be seen that in one position of the pawls, the chuck will be wholly disengaged from both arms.

As a means for controlling the movement of the pawls I have provided the wrench head with an arcuate shaped recess or channel 36 in which is positioned a bowed leaf spring 37 which is held under tension by means of the spaced pins 38 and the free ends of which are perforated to receive the ends of laterally directed pins 39 carried by the pawl members. The central portion of this spring is perforated to receive the reduced terminal 40 of a lever arm 41 which is seated in a longitudinally extending recess 42 formed in the rear portion of the head and which is pivoted intermediate its length upon a pivot pin 43 carried by the head of the wrench. The rear end of this recess 42 is enlarged to form a chamber 44 and extending transversely of this chamber and journaled by its ends in suitable bearings formed in the side walls thereof, is a worm shaft 45 which is passed through a threaded bore formed in the free end of the lever 41 and which is provided adjacent one end with a milled nut 46 by means of which it may be rotated to swing the lever from one side to the other, this swinging of the lever acting through the leaf spring 37 to swing the locking pawls. The face plate 18 is so constructed as to cover the pawl receiving chambers and the arcuate recess 36 and is provided at its forward end with oppositely curved arms or extensions which seat upon the shoulder 16 surrounding the chuck and which extend slightly over the chuck to prevent its disengagement from the head of the wrench.

In order to adapt the wrench for em-

ployment with nuts of various sizes, I have provided a plurality of nut engaging members 47, each including a base having a cylindrical extension adapted to seat in the socket 21 of the chuck and spaced side members provided upon their outer faces with longitudinally extending ribs adapted to engage the grooves of the nut receiving recess of the chuck. As will be readily understood, I form these members 47 with sides of various thicknesses, thereby producing various sized nut receiving sockets.

In Fig. 6, I have illustrated a further modification of nut engaging member, designated as a whole by the numeral 48 and including a body member 49 formed with a cylindrical extension 50 and ribs 51 for engagement with the recess of the chuck member and formed with upwardly directed, spaced apart arms 52 adapted to be inserted in the end of a wheel hub for engagement with the spindle nut.

From the foregoing description, taken in connection with the drawing, the operation of my improved wrench will be apparent. In the various views I have illustrated the wrench adjusted for loosening a nut from its bolt, the upper arms 34 of the pawls both being in engagement with the teeth 24 of the chuck to hold the chuck against clockwise rotation in the wrench head.

By turning the milled nut 46, the lever 41 may be swung toward the opposite side of the head to swing the arm 34 of the pawls out of engagement with the chuck and the arms 35 into engagement therewith, when the wrench will be ready to thread nuts upon bolts.

From the foregoing description, it will be apparent that I have provided a simple and effective form of wrench of the ratchet type, in which there are but few parts, and these so simply formed and correlated as to insure perfect action at all times.

Having thus described the invention, what is claimed as new is:

1. A ratchet wrench including a head apertured to receive a chuck member and chambered to receive a ratchet mechanism, a cylindrical chuck member rotatably mounted in said head, oppositely formed sets of ratchet teeth extending from the peripheral face of said member, double-armed pawls mounted for movement in the chambers of the head, the upper arms of said pawls being adapted for engagement with one set of teeth of the chuck member, while the lower arms of the pawls are adapted for engagement with the other set of teeth of the chuck member, means for swinging said pawls simultaneously to bring either of their arms into operative position, said means including laterally directed pins carried by the pawls, a resilient member connected by its ends to said pins, a lever pivoted interme-

diate of its length and connected by one end to said resilient member, and means for swinging the free end of said lever laterally and for locking said lever in adjusted 5 position.

2. A ratchet wrench including a head, a chuck rotatable in said head, pawls mounted in said head and having arms adapted for engagement with ratchet teeth formed 10 upon the chuck, laterally directed pins extending from said pawls, a bowed leaf spring secured by its ends to said pins, a

lever pivoted intermediate of its length and secured by one end to the central portion of said spring, a worm shaft threaded through 15 the free end of said lever and journaled in the head, and means for rotating said shaft.

In testimony whereof I affix my signature in presence of two witnesses.

JOHN E. HITT. [L.S.]
